UNITED STATES PATENT OFFICE.

ELMER O. BEARDSLEY AND WALTER F. PIPER, OF CHICAGO, ILLINOIS, ASSIGNEES TO THE BEARDSLEY & PIPER COMPANY, OF CHICAGO, ILLINOIS, A CORPORATION OF ILLINOIS.

MACHINE FOR MAKING MOLDS.

Application filed December 31, 1921, Serial No. 526,199. Renewed March 28, 1924.

To all whom it may concern:

Be it known that we, ELMER O. BEARDSLEY and WALTER F. PIPER, both citizens of the United States, and residents of Chicago, in the county of Cook and State of Illinois, have invented certain new and useful Improvements in Machines for Making Molds, of which the following is a full, clear, and exact description.

- 10 The invention relates to machines for making molds and more particularly to those embodying a high-speed projector for rapidly filling and packing sand into flasks containing patterns.
- 15 The primary object of the invention is to provide means for delivering flasks to and from a projector with facility, so that the idle periods of the projector will be reduced to a minimum and the output will be increased. Other objects will appear from the description of the machine.

The invention consists in the several novel features hereinafter set forth and more particularly defined by claims at the conclusion hereof.

In the drawings: Fig. 1 is a side elevation of a machine embodying the invention. Fig. 2 is a view showing the driving mechanism at one side of the machine. Fig. 3 is a plan. Fig. 4 is a section on line 4-4 of Fig. 3. Fig. 5 is a detail of the brake for the turntable. Fig. 6 is a front elevation. Fig. 7 is a detail of the projector.

The invention is exemplified in a machine comprising a portable carriage equipped with a projector and mechanism for feeding sand from a pile on the floor to the projector and a turntable movable with the carriage and adapted to deliver the flasks to and from a point where they may be readily filled by the projector.

The carriage comprises sides 11, tubular cross-members 12, 13 which are rigidly secured to the sides by U-bolt clamps 14, toothed traction wheels 15, adapted to run on tracks 16 in the foundry-floor and to mesh with racks 17 on the tracks, and wheels 18. The carriage is propelled to advance the machine over and into a pile of sand on the floor by an electric motor 19 secured to a bracket 20 which is fixed to the carriage,

a pinion 21 on the shaft of said motor, a gear 22 driven by said pinion, a pinion 23 integral with gear 22, a gear 24, a cross-shaft 25 fixed to gear 24, a wrist-pin 26 fixed to one end of shaft 25, a pawl 27 operated by said wrist-pin and adapted to stop up a ratchet-wheel 27^a, and a pinion 28 integral with the ratchet and meshing with one of the toothed traction wheels 15. The latter are cross-connected so they will be synchronously driven by a cross-shaft 29 which extends through the tubular frame-member 13.

The projector comprises a casing or stator 30, a rotor 31 provided with a blade 32 for projecting wads of sand at high-speed into the flasks 33; a tubular arm 34 on the outer end of which the projector is sustained; a rotor-shaft 35 extending through arm 34; an electric motor 36 mounted on the inner end of said arm and geared to drive shaft 35; and a jib 36^a to the outer end of which arm 34 is pivoted and having its inner end pivotally sustained by a standard 37 which is suitably secured to the tubular members 12 and 13 of the carriage. This post is disposed at one side of the carriage so that the projector may be moved over a flask disposed centrally over the carriage and laterally of the post, the jib and arm being provided to permit the projector to be moved laterally to fill all portions of a flask without varying the angle of delivery of the sand.

The mechanism for feeding sand to the projector from a pile of prepared sand on the foundry-floor and between the tracks 16 comprises a helical conveyor 38 which is fixed to and driven from motor 19 by shaft 25, and is provided with blades 39 for disintegrating the sand and adapted to feed the sand crosswise of the carriage to a point adjacent to one side of the carriage, an elevator having a series of buckets 40^a on an endless chain 40, a sprocket 41 fixed to shaft 25 so it will be driven from motor 19 and the gearing heretofore described, and so it will drive the elevator, an idler sprocket 42 for the upper end of the chain 40 and a shaft 43 for said idler sprocket, which is mounted in levers 44 which are pivoted to standards 45 and are pressed and held in

position to keep the chain taut by a spring-connection 46. The screw-conveyor 38 with its blades 39 feeds the sand crosswise from the pile on the floor to the elevator-buckets 40^a which discharge the sand into a guide 70. A vibratory chute 47 is supported on and to move with the jib 36^a, receives the sand from guide 70, and is extended to clear the elevator and discharge the sand onto a belt 48 which is movable with the arm 34. A screen 49 is provided in chute 47 to catch scrap and clods and prevent them from passing to the projector. The chute 47 is sustained on and vibrated by a motor on the jib, and belt 48 is sustained on arm 34 and driven from motor 36, as more fully shown in Patent No. 1,408,493, granted to us May 7, 1922, to which reference may be had for a detail description thereof. The belt 48 feeds the sifted sand to the projector in regular quantity so the projector lade will forcibly sling wads of sand into the flasks.

Mechanism adapted to deliver flasks to and from the projector is mounted to travel with the projector carriage and comprises a turntable 50 on which a series of plates 51, each adapted to support a flask 33, are secured. The turntable is provided with a hub 52 which is journaled in a bearing 53 which is secured by bolts 54 to a truck which is connected to the projector carriage. This truck comprises a frame composed of sills 55 and an axle 56 which carries a roller 57 and secures the sills together. The front ends of the sills 55 are each pivoted to a pin 58 which is carried in a block 59 which is secured by a U-clamp 60 to the tubular member 13 of the projector carriage. This truck rotatably supports the turntable for the flasks so it will be advanced with the projector carriage and projector. The plates 51 are arranged so they will successively pass into position to bring the flasks thereon beneath the projector 30 and to bring them into position so the flasks may be conveniently removed therefrom and re-loaded while the projector is filling a flask, that is to say, while one flask is being filled with sand, other flasks may be placed on some of the plates 51 in readiness to be successively conveyed into operative relation and be filled by the projector, so that filled flasks may be simultaneously removed from some of the other plates 51. As a result, the idle periods of the projector are reduced to a minimum. Each plate 51 is provided with pins 61 to slip into the usual lugs on the flasks.

A brake is provided to secure the turntable in its assigned positions to successively hold the flasks under the projector. This brake comprises a brake-band 62 adapted to grip a friction drum 63 on the turntable and having one of its ends secured, as at 64, to one of the sills 55 and its other end connected, as at 65, to a lever 66 which is pivoted to

said sill at 67. Studs 68, carried by the turntable 50, are adapted to engage the lever 66 to hold it in position to retain the brake-band 62 in operative position. The outer end of lever 66 is provided with a foot-piece 69. As the flasks are successively filled by the projector, the operator will depress treadle 69 sufficiently to clear its coacting stud 68. The turntable will then be released so it can be rotated to bring an empty flask 75 on one of the plates 51 into position to be filled.

The operation of the machine will be as follows: While the projector-carriage is being propelled forwardly, the cross-conveyor 38 and elevator 40, 40^a will deliver sand into the chute 47, in which it will be sifted. The sifted sand from chute 47 will be discharged onto the feed-belt 48 carried by the arm 34 and which will supply sand to the projector 30, 31 in regulated quantity. Flasks with patterns therein will be placed on the plates 51 at one side of the plate disposed beneath the projector, and the turntable will then be rotated one step to bring an empty flask 90 into operative range of the projector. The operator in charge of the projector will manipulate it over said flask until it has been properly filled and packed with sand. Another operator will keep the plates 51 approaching the projector loaded with flasks, so that as soon as one flask has been filled another may be brought into operative range of the projector by rotating the turntable one step. Simultaneously, other workmen will lift the filled flasks from the plates 51 which have passed away from the projector. During each shifting operation of the turntable, one of the operators will first release lever 66, rotate the turntable one step and then set the lever to apply the brake-band 62 so the turntable will be secured against rotation.

The invention exemplifies a moulding machine in which provision is made for speedily and successively bringing empty flasks into position to be filled by the projector and to be removed so that the idle periods of the projector will be reduced to a minimum. By facilitating the delivery of the flasks to the projector and their removal when filled, the output of the projector is materially increased over methods heretofore employed, in which the projector necessarily remained idle while the flasks were being manually brought to and removed from the projector.

The invention is exemplified in connection with a portable moulding machine, although it is to be understood that certain features thereof are applicable to a projector in which the supporting jib is pivoted to a stationary column, in lieu of a column on a portable carriage.

While the invention has been illustrated in connection with a projector, it is to be under-

stood that certain features of the invention may be used with other means for delivering sand from the elevator to the flasks on the turntable and that the claims are not to be understood as restricted to combinations including a projector, except where the same is specified.

The invention is not to be understood as restricted to the details set forth, since these 10 may be modified within the scope of the appended claims, without departing from the spirit and scope of the invention.

Having thus described the invention, what we claim as new and desire to secure by 15 Letters Patent, is:

1. In a moulding machine, the combination with a rotary sand projector bodily and horizontally movable in any direction to project sand into all portions of a flask, and 20 means for feeding sand thereto, of mechanism for conveying flasks into and out of position to be filled by the projector.

2. In a moulding machine, the combination with a rotary sand projector, a portable carriage on which the projector is mounted, driving mechanism for the projector movably mounted on the carriage, and means 25 for feeding sand to the projector, of mechanism for conveying flasks into and out of position to be filled by the projector.

3. In a moulding machine, the combination with a rotary sand projector, means to movably support the projector for bodily horizontal movement over all portions of 35 a flask, means to drive the projector bodily movable therewith and means for feeding sand to the projector, of mechanism for conveying flasks into and out of position to be filled by the projector.

4. In a moulding machine, the combination with a rotary sand projector bodily and horizontally movable in any direction to project sand into all portions of a flask and 40 means for feeding sand thereto, of a carrier provided with means for supporting a series of flasks and rotatable to successively bring the flasks into and out of operative relation to the projector.

5. In a moulding machine, the combination with a rotary sand projector, a portable carriage on which the projector is mounted, driving mechanism for the projector mounted on the carriage and means for feeding sand to the projector, of a carrier provided 55 with means for supporting a series of flasks and rotatable to successively bring the flasks into and out of operative relation to the projector.

6. In a moulding machine, the combination with a rotary sand projector, means to movably support the projector for bodily and horizontal movement over all portions of a flask, driving mechanism for the projector including a motor movable with the projector and means for feeding sand to the 60 projector.

projector, of a carrier provided with means for supporting a series of flasks and rotatable to successively bring the flasks into and out of operative relation to the projector.

70

7. In a moulding machine, the combination of a portable carriage, a sand projector mounted on the carriage, mechanism on the carriage for operating the projector, mechanism on the carriage for feeding sand 75 to the projector, and means to support a series of flasks and successively convey them into and out of operative relation to the projector.

8. In a moulding machine, the combination of a portable carriage, a sand projector mounted on the carriage and movable over a flask and relatively to the carriage, mechanism on the carriage for operating the projector, mechanism on the carriage for 80 feeding sand to the projector, and a conveyor provided with means to support a series of flasks and successively convey them into and out of operative relation to the projector.

90

9. In a moulding machine, the combination of a portable carriage, a sand projector mounted on the carriage, mechanism for operating the projector, mechanism for feeding sand to the projector, and a support movable with the carriage provided with means for conveying flasks successively 95 into and out of operative relation to the projector.

10. In a moulding machine, the combination of a portable carriage, a sand projector mounted on the carriage, mechanism for operating the projector, mechanism for feeding sand to the projector, and a rotatable support movable with the carriage and provided with means for conveying flasks successively 100 into and out of operative relation to the projector.

105

11. In a moulding machine, the combination of a portable carriage, a sand projector 110 movably mounted on the carriage, mechanism for operating the projector, mechanism for feeding sand to the projector, and a support movable with the carriage and provided with means for conveying flasks successively into and out of operative relation to the projector.

115

12. In a moulding machine, the combination of a sand projector, mechanism for operating the projector, mechanism for feeding sand to the projector, a truck connected to the projector and a conveyor mounted on the truck, provided with means for conveying flasks successively into and out of 120 operative relation to the projector.

125

13. In a moulding machine, the combination of a portable carriage, a sand projector mounted on the carriage, mechanism for operating the projector, mechanism for feeding sand to the projector, a truck con- 130.

nnected to said carriage and a conveyor mounted on the truck, provided with means for conveying flasks to successively bring them into and out of operative relation to the projector.

14. In a moulding machine, the combination of a portable carriage, a sand projector mounted on the carriage, mechanism for operating the projector, mechanism for feeding sand to the projector, a truck connected to said carriage and conveyor rotatably mounted on the truck and provided with means for conveying flasks to successively bring them into and out of operative relation to the projector.

15. In a moulding machine, the combination of a portable carriage adapted to travel longitudinally over a moulding room floor, power-driven means for slowly propelling the carriage, a power-driven sand-elevator mounted on the carriage, means to convey the sand laterally from a pile on the floor to the elevator, a turn-table movable with the carriage adapted to hold flasks and successively bring them into and out of position to receive sand, and means for delivering sand from the elevator into and to successively fill flasks.

16. In a moulding machine, the combination of a portable carriage adapted to travel longitudinally over a moulding-room floor, power driven means for propelling the carriage, a power driven sand elevator mounted on the carriage, means to cut the sand and convey it laterally from a pile on the floor to the elevator, a turn-table movable with the carriage, adapted to hold flasks and successively bring them into and out of position to receive sand, and means for delivering sand from the elevator into the flasks.

17. In a moulding machine, the combination of a portable carriage adapted to travel longitudinally over a moulding-room floor, power-driven means for propelling the carriage, a power-driven sand elevator mounted on the carriage, means to convey the sand laterally from a pile on the floor to the elevator, a turn-table movable with the carriage for holding flasks and successively bringing them into and out of position to receive sand, a screen into which sand is delivered by the elevator, and means to deliver the

sand from the screen into the flasks on the turn-table.

18. In a moulding machine, the combination of a portable carriage adapted to travel longitudinally over a moulding-room floor, power driven means for slowly propelling the carriage, a power-driven sand-elevator mounted on the carriage and at one side thereof, means to convey the sand laterally from a pile on the floor to the elevator, a projector mounted at the same side of the carriage, and means to deliver sand from the elevator to the projector.

19. In a moulding machine, the combination of a portable carriage adapted to travel longitudinally over a moulding-room floor, power driven means for slowly propelling the carriage, a power-driven sand-elevator mounted on the carriage and at one side thereof, means to convey the sand laterally from a pile on the floor to the elevator, a turn-table movable with the carriage for holding flasks and successively bringing them into and out of position to receive sand, and means for delivering sand from the elevator into the flasks.

20. In a moulding machine, the combination of a portable carriage adapted to travel longitudinally over a moulding-room floor, power driven means for slowly propelling the carriage, a power-driven sand-elevator mounted on the carriage and at one side thereof, means to cut the sand and convey it laterally from a pile on the floor to the elevator, a projector mounted at the same side of the carriage, and means to deliver sand from the elevator to the projector.

21. In a moulding machine, the combination of a portable carriage adapted to travel longitudinally over a moulding-room floor, power driven means for slowly propelling the carriage, a power-driven sand-elevator mounted on the carriage and at one side thereof, means to cut the sand and to convey it laterally from a pile on the floor to the elevator, a turn-table movable with the carriage for holding flasks and successively bringing them into and out of position to receive sand, and means for delivering sand from the elevator into the flasks.

ELMER O. BEARDSLEY.
